UNITED STATES PATENT OFFICE.

LOUIS H. LANDRY, OF UXBIDGE, MASSACHUSETTS, ASSIGNOR OF ONE-EIGHTH TO UDGIL LAROCQUE AND ONE-HALF TO SAMUEL B. TAFT, BOTH OF UXBIDGE, MASSACHUSETTS, AND ONE-EIGHTH TO LOUIS BOUSQUET AND THEODORE BOUSQUET, BOTH OF BURRILLVILLE, RHODE ISLAND.

SMASH-PROTECTOR.

1,071,244.

Specification of Letters Patent.

Patented Aug. 26, 1913.

Original application filed July 24, 1908, Serial No. 445,155. Divided and this application filed August 14, 1909. Serial No. 512,785.

To all whom it may concern:

Be it known that I, LOUIS H. LANDRY, a citizen of the United States, residing at Uxbridge, in the county of Worcester and State 5 of Massachusetts, have invented a new and useful Smash-Protector, of which the following is a specification.

This invention relates to a smash protector for looms and is a division of my Patent No. 943,028, granted Dec. 14, 1909, on a loom, the application for which was filed July 24th, 1908, Serial No. 445,155.

The principal objects of this invention are to provide a simple construction capable of 15 working without the complications usually thought necessary in this art for the purpose of indicating absolutely whenever the drop boxes start to change when a shuttle is not in proper position therein; to provide a box 20 guide designed to prevent the shuttle from tripping, the bobbin from splitting; the shuttle from flying out, and the filling from cutting; and to provide means operated thereby whereby the loom will be stopped 25 when such condition of affairs exists.

Another object of the invention is to provide for securing the above mentioned results by adding only a few parts to the ordinary loom construction.

30 Further objects and advantages of the invention will appear hereinafter.

Reference is to be had to the accompanying drawings, in which—

Figure 1 is a front elevation of a portion 35 of the front box guide of a loom showing one embodiment of this invention applied thereto; Fig. 2 is an end view of the same partly in section; Fig. 3 is a plan view thereof; and Fig. 4 is an elevation showing 40 certain connections for stopping the loom.

The invention is shown applied to a loom having on the lathe 10 thereof, a shuttle box guide 11 for the shuttle box 12. From

each end of the lathe a plate 13 extends upwardly provided with a slot 14.

In order to stop the loom in case a shuttle is left part way in or part way out of the shuttle box as the latter rises, a feeler 15 is provided on the lathe above the path of the shuttle so that as the shuttle box rises, 50 if a shuttle is under the feeler it will cause the feeler to swing on its pivot against a spring 16 and to turn a lever 17 passing through the slot 14. The end of this lever operates through a system of levers 18 on 55 a finger 19 to turn the shipper lever 20 and stop the loom. This stops the picking motions at both ends of the loom, and provides for operating the shipper lever automatically to stop the loom without interfering 60 with the ordinary hand-operation of the shipper lever. The levers 18 are pivoted at 21 on the frame.

While I have illustrated and described a preferred embodiment of the invention, I 65 am aware that many modifications can be made therein by any person skilled in the art without departing from the scope of the invention as expressed in the claims. Therefore I do not wish to be limited to 70 all the details of construction shown and described, but

What I do claim is:—

1. In a loom, the combination of a shuttle box, means for raising and lowering it, 75 a feeler located adjacent to the inner end thereof in position to be engaged by a shuttle protruding from the box when the box is raised, said feeler consisting of a pivoted plate, a spring for holding the plate down, 80 a lever resting on the top of said plate and having a projection, and means cooperating with said projection for stopping the loom.

2. In a smash preventer for looms, the combination of a pivoted plate, means for 85 holding it in position to be engaged and

raised positively by the shuttle when protruding from the box as the box rises and adapted to drop when the shuttle is absent, and means connected with the plate for 5 stopping the loom when the plate rises.

3. In a loom, the combination with a lathe, and a shuttle box guide thereon, of a feeler pivoted above the lathe, a spring for normally holding the feeler down to the 10 level of a shuttle in the shuttle box, a shipper lever having a finger thereon, and a system of levers adapted to be operated by the

feeler and engaging one side of the finger on said shipper lever for positively operating said shipper lever to stop the loom when 15 the feeler moves in one direction.

In testimony whereof I have hereunto set my hand, in the presence of two subscribing witnesses.

LOUIS H. LANDRY.
